UNITED STATES PATENT OFFICE.

ANSON C. TICHENOR, OF ALAMEDA, CALIFORNIA, ASSIGNOR TO E. K. VALENTINE, OF CUMING COUNTY, NEBRASKA.

PROCESS OF TREATING ALCOHOLIC LIQUORS WITH ELECTRICITY.

SPECIFICATION forming part of Letters Patent No. 280,882, dated July 10, 1883.

Application filed April 20, 1883. (No model.)

To all whom it may concern:

Be it known that I, ANSON C. TICHENOR, a citizen of the United States, residing at Alameda, Alameda county, State of California, have made and invented certain new and useful Improvements in Treating Alcoholic Liquors with Electricity, to purify and impart to them the character of age; and I do hereby declare that the following is a full, clear, and exact description of my said invention, reference being had to the accompanying drawings.

My invention relates to an improvement in the method or process of treating alcoholic liquors with electricity to separate and extract those acrid oils, alcoholic principles, and matters of poisonous and deleterious properties which in the ordinary course of treatment are removed or thrown off by age.

The following description fully explains the nature of my said invention and the manner in which I proceed to apply, use, and carry out the same, reference being had to the accompanying drawings, in which—

Figure 1 is a section of the apparatus I use, showing the wires which come from the source of electricity. Fig. 2 is a detail of an electrode, and Fig. 3 is the fibrous or textile covering herefor.

A is the vessel to hold the liquor, of capacity to hold, say, a barrel of liquor. It is electrically isolated by being placed on an insulated base, and a light cover or frame of wire-gauze or thin material is placed over it to exclude dust and insects.

An electric generator is provided, from which conductors C C' are carried to the vessel, where connection is made to poles or plates D D', forming the electrodes.

The best results are obtained by using tubs or vats of about one-barrel capacity and a dynamo-electric machine having a strength or power equal to a Daniells battery of forty cells. Conductors C C' are then led to each receptacle and connected with a pair of electrodes in each. Where several receptacles are used in this manner, they should be of about uniform capacity.

The electrodes D D' are plates or poles of carbon or metal. The positive one, D, is made one-third larger than the negative one, D'.

They are inserted into the liquor at opposite sides of the tub or receptacle, so that their active surfaces are covered by the liquor, and they are placed as far apart as the diameter or size of the tub will admit. The full strength 55 of the electric current from the generator is then applied directly through the liquor, and it is maintained for a length of time or number of hours varying with the size and power of the machine, and governed also by the kind of 60 liquor being treated.

This process or operation is substantially the same both in treating whisky and such heavy liquors and in operating on wines and lighter grades of liquors; but in working wines I place 65 the liquor in close casks or receptacles, having the conductors inserted through an aperture in the side, so that the cask can be sealed up while the contents are being acted on. For electrodes the metal plates are best adapted for 70 wines; but carbon poles should be used for whisky. The strength of current from the generator, in working wines, should be reduced also to about one-third of that used for heavier liquors—say from ten to fifteen cell power. In 75 the course of this operation of the electric current it will be found that the impurities and matter separated and thrown out from the body of liquor are deposited upon the surface of the negative or small plate, and in a short 80 time this surface becomes thickly coated or covered with a slimy or viscid substance that requires to be removed and the surface of the plate or pole kept clean for proper action. This cleansing is accomplished in a simple and 85 effective manner by simply wrapping or surrounding the plate with a removable case or cover, E, of felt, canton-flannel, woolen cloth, or other fibrous or textile material that, while not interfering with the action of the current, 90 will yet protect the plate and constitute a removable receiving and absorbing surface. All the matter and substances extracted by the current and precipitated or attracted to and deposited upon this surface are then readily 95 taken out by lifting the plate and removing the wrap or cover. This improvement enables the plate to be cleaned without interference with the continuity of the operation, as the wraps or covers are quickly removed and re- 100

placed by clean ones. The absorbing character or quality of the wrapping is also of advantage in taking up the extracted matter.

I am aware that in the process of aging liquors it has been found that fusel-oils, &c., will gather on one electrode; and I am also aware that in coating metals by electric deposition one of the electrodes has been covered with a porous, fibrous, or textile covering for the purpose of gathering the material; hence I do not claim such.

Having thus fully described my invention, what I claim as new, and desire to secure by Letters Patent, is—

15 The method of removing fusel-oils or other

impurities from alcoholic liquors, which consists, first, in passing through them an electric current by means of wires and electrodes one of which is provided with a removable envelope or casing; and, secondly, in removing said envelope from the liquor and renewing it by putting on another or cleansing and restoring the old envelope at intervals when it has received a deposit of impurities, substantially as herein set forth.

ANSON C. TICHENOR. [L. S.]
